UNITED STATES PATENT OFFICE

2,278,823

DISHWASHING MACHINE

Tord Erik Daniel Bilde, Ulvsunda, Sweden, assignor to Bolinder's Fabriks Aktiebolag, Stockholm, Sweden, a corporation of Sweden.

Application February 14, 1940, Serial No. 318,928
In Germany March 2, 1939

6 Claims. (Cl. 103—25)

The present invention relates to dish washing machines which are provided with a pump or pumps for forwarding a liquid or liquids serving for cleaning the dishes and with an electric motor for driving said pumps.

In dish washing machines of this type it is the most obvious proceeding to make the means for setting the valve or valves and the means for setting the switch controllable independently of each other. In doing this, however, these means must be operated in a definite sequence relatively to one another in order to ensure a safe operation of the machine. For example, if the valve setting means is actuated whilst the motor and accordingly the pump are still in operation the setting of the valve will be rendered more difficult or even impossible, as a relatively large expenditure of energy is necessary in order to overcome the pump pressure which not infrequently is high. The operation of the machine presupposes under such circumstances a certain expert knowledge, which it is sought to avoid, however, as the operation of such machines is usually entrusted to more or less unskilled persons.

The principal object of the invention is to eliminate these difficulties and to provide a dish washing machine of the type described in which the valve or valves and the switch are positively controlled so as to permit their operation only in the correct sequence, thereby ensuring an automatic and safe operation of the machine.

Another object of the invention is to provide a dish washing machine of the type described in which the means for setting the valve or valves and the means for setting the switch are so combined with each other that actuation of the valve setting means is prevented, when the motor is switched-on, and permitted only when the switch is set to open the circuit of the motor. Preferably the connection of the valve setting means and the switch setting means are such that in addition to the above said blocking of the valve setting means, when the motor is switched-on, actuation of the switch setting means to close the circuit switch on the motor is prevented when the valve is closed and permitted only when the valve setting means is set to open the valve.

These and further objects of the invention will be apparent according as the following description proceeds, reference being had to the accompanying drawings in which:

Figs. 1 and 2 represent two different positions of setting of two knobs arranged to operate the

valve setting means and the switch, respectively, the said knobs mutually blocking one another according to the invention.

Fig. 3 is a side elevation, partly in section, of a dish washing machine arranged according to the invention.

Fig. 4 is a front elevation of this machine, also partly in section.

Fig. 5 is a sectional view of a control box.

Figs. 6 to 8 represent a switch in various positions.

Fig. 9 illustrates a thermostat and the connection thereof to the switch.

Fig. 10 is a current diagram.

Fig. 11 shows a modification of the machine according to Figs. 3 and 4.

In Figs. 1 and 2, 10 represents a knob for operating the switch of an electrically operated dish washing machine, and 11 a knob for operating two valves of the machine, which is provided with two pumps each controlled by one of these valves for washing or rinsing liquid, respectively. The spindles 12 and 14 of the knobs carry each a disk 15 and 16, respectively, which disks are of equal diameter. The distance between the centres of the disks is less than their diameter and the disks are provided with recesses of a shape as to make both of the disks freely movable when a recess in one of the disks is opposite a recess in the other disk. The disk 15 has one recess 17 and the disk 16 two recesses 18 and 19 corresponding each to open position of one of the valves. In the position according to Fig. 1, corresponding to switched-out motor and closed valves, knob 10, as will be seen, cannot be set, or in other words, the motor cannot be switched-on, whereas knob 11 on the other hand is freely settable. Knob 10 can only be set, or in other words, the motor switched-on when knob 11 is turned in one direction or the other through such an angle that one of the recesses 18 or 19 is opposite the recess 17, that is to say one of the valves has been opened. In this position of the knobs which is represented in Fig. 2, knob 10 can be freely set whilst knob 11 is locked, that is the valves cannot be set, such setting of the valves becoming possible only when knob 10 is re-set into the rest position according to Fig. 1 in which the motor has been switched-off.

In the embodiment represented in Fig. 3 the locking disks 22 and 23 mounted on the spindles 20 and 21 of two knobs for the operation of the machine (not visible) are arranged at a distance from one another and each provided with a single recess 24 and 25, respectively. Arranged be-

tween the disks is a tube 26 in which two plungers 27 and 28 can move, said plungers being mounted in bearings outside the tube at 29 and 30, respectively, and each capable of engaging one of the recesses. A spring 31 arranged in the tube 26 between the two plungers presses them outwards against the corresponding disk.

In the figure both of the blocking disks are represented as being in their rest position. If, for example, the knob mounted on the spindle 20 is turned, plunger 27 is pushed inwards of the tube causing compression of spring 31. An abutment 27a on plunger 27 moves loose tube 26 against plunger 28 and an abutment 28a on it, whereby plungers 27, 28 and tube 26 form a rigid blocking unit for disk 23. Thus, in their rest position the blocking disks 22, 23 are only elastically blocked and any one of them can be freely turned in one direction or the other, but if a blocking disk has been turned out of its rest position, the other disk will be positively blocked in such a way, that its turning is prevented. Also in this case the knobs control a switch or one or more valves, respectively.

In Figs. 1 and 2 the connections between the knobs and the switch or the valve setting means, respectively, are not shown. They can be of any desired form or design and consist, for example, of ropes, rods etc.

The dish washing machine as shown in Figs. 3 to 10 will first be described in respect of its general design by reference to Figs. 3 and 4.

40 indicates a housing built in a washing bench 41 and supported by an upper flange 42 on a shoulder 43 provided around an opening in the top panel of the bench. The housing is closed at the top by a lid 45 connected to the housing by hinges 44 and lying, when in its closed position, in flush with the upper surface of the bench. The housing forms a spraying chamber 46 for the dishes and at its bottom it is formed to provide a reservoir which is divided by two sloping walls 47, 48 into two compartments, one 49 for washing liquid and the other 50 for rinsing liquid. A motor pump unit consisting of an electric motor 51 and pumps 52, 53 arranged on either side of the motor is arranged underneath the spraying chamber 46 and behind the liquid reservoir. A suction pipe 54 for pump 52 is connected to an orifice at the bottom of the washing compartment 49 and controlled by a lift valve 55, the valve rod 56 of which passes through the wall of pipe 54. A suction tube 57, lift valve 58 and valve rod 59 of pump 53 are arranged in similar fashion with regard to the rinsing liquid compartment 50. At the lowermost point of the washing pump 52 is a discharge pipe 60 controlled by a valve (not shown), the rod 61 of which is conducted through the wall of the discharge pipe 60. 62 is an overflow pipe leading from the washing compartment 49.

The washing pump 52 is connected through a rising pipe 63 to a spraying device for washing liquid, which consists in this case of a spray pipe 64 swingable horizontally to and fro in the lower part of the spraying chamber. A similar rising pipe 65 connects rinsing pump 53 to a spraying device for rinsing liquid, comprising a fixed spray pipe 66 arranged in the lower part of spraying chamber 46.

67 designates a control box enclosing all the electrical members of the machine and fixed to the bottom of the motor frame 51. As will be described further below a switch enclosed in the box controls the motor as well as an electric

heating element 68 provided in the rinsing compartment 50, the conductors 69 of which element are led into said box through a tube 70. 71 represents the current carrying cable.

5 Fixed to a shaft 72 is a double-armed lever 73 which is located just underneath valve rods 56 and 59 and connected to each of said rods by links 74 and 75, respectively, a pin 76 on the lever 73 engaging an elongated slot 77 in the link, said shaft 72 being rotatably mounted in the wall of the control box 67 and carrying inside said box an operating member arranged to control the switch in a manner to be described further below. The arrangement is such that at each end position of lever 73 one valve is open and the other closed. A rope 78 is fastened at its ends to the ends of lever 73 and conducted over guiding rollers 79 to a switch panel 80 provided at the front of the machine housing and accessible through an aperture in the door 41a of the washing bench. This switch panel carries a knob 81, whose spindle 81a carries an arm 82 to the free end of which rope 78 is connected. When knob 81 is turned in one direction or the other, valves 55, 58 will accordingly be opened and closed alternately.

Another knob 83 provided on switch panel 80 carries on its spindle 83a an arm 84 which is connected by a rope 85 conducted over a guiding roller 86 to bell crank lever 87 controlling the valve rod 61 of the discharge valve of the washing pump 52 which valve is kept in the closed position by a spring 88. Mounted on the same shaft 83a inside the machine housing is an upwardly directed arm 89 which by a roller 90 engages the underside of the lid 45 and serves to raise said lid by a small angle, so that it can be gripped manually.

As will be described in further detail below, the switch is also arranged to be actuated by a thermostat comprising a bimetal body 91 arranged at the bottom of the rinsing compartment 50 and acting on a spindle 92 conducted through the wall of box 67 and carrying inside the box an operating member which acts on the switch. At its free end spindle 92 carries a button 93 accessible through an opening in door 41a.

As will be seen from Fig. 5 the control box 67 is fixed by screws 94 to the base of the electric motor frame 51. The control box has an elongated form and contains at one end a terminal block 95 for the motor and at the other end a switch indicated in its entirety by 96. In the embodiment shown the switch comprises a double pole two-way rocking switch with two mercury rockers 97, 98 each having two pairs of contacts, which are connected to the source of current, the motor and the heating element in the manner shown in Fig. 10.

According to the diagram shown in this figure the incoming conductors 71 are each connected to the inner contacts 97b, 97c and 98b, 98c, respectively, of the contact pairs of the two rockers 97 and 98, respectively, whilst the motor 51 is connected over conductors 99 to the outer contacts 97a, 98a of one of the contact pairs and the heating element 68 over conductors 69 to the outer contacts 97d, 98d of the other contact pair. Thus, the motor 51 and the heating element 68 are connected in parallel to the switch, the motor being switched-on at one and the heating element at the other of the contact-making positions, whereas the switch is currentless in the midway position of the rockers.

The two mercury rockers 97, 98 are fixed to a

common frame 100 with side plates 101 and 102, plate 101 being fixed to a hollow shaft 103 mounted in the control box and plate 102 mounted on a pin 104 fixed to shaft 12. Subject to the action of spring 105 the hollow shaft tends to turn frame 100 with rockers 97, 98 counter-clockwise as viewed from the right in Fig. 3. The motor conductors from and to the switch are conducted through the hollow shaft 103. By reason of the relatively large distance between switch 96 and terminal block 95 all risk of conductor breakage is avoided.

As already mentioned above, valve rod 73 is fixed to the shaft 12, for example by a pin 106. An arm 107 provided inside the box 67 is fixed to shaft 12 or formed integral therewith. At its free end arm 107 carries a roller 108 cooperating with a rocking lever 110 pivoted on a pin 109 fixed to the wall of the control box, this lever having three recesses 111, 112, 113, into which the roller 108 engages in various positions. As mentioned above frame 100 with mercury rockers 97, 98 is under the action of the spring 105 shown in Fig. 5 urged in counter-clockwise direction as viewed in Figs. 6 to 9, this rotation being limited by the engagement of a pin 114 provided on frame plate 102 with rocking lever 110 locked by arm 107.

In Figs. 6 to 8 valve rod 73 is indicated in dash lines 73a.

In the position of the switch as shown in Fig. 6, rinsing valve 58 is open and accordingly washing valve 55 closed. The motor is switched-on, that is to say the machine assumes rinsing position. In this position roller 108 engages the right-hand recess 111 in rocking lever 110 and the switch assumes its right-hand end position. If the machine is to be set for washing, knob 81 is turned in clockwise direction as viewed in Fig. 4, whereby lever 73 and hence also arm 107 are turned in counter-clockwise direction as viewed in Fig. 6. By this means rocking lever 110 and hence also frame 100 are released, the latter being under the action of spring 105 turned counter-clockwise carrying with it rocking lever 110. In this way the motor circuit is broken. When lever 73 has attained horizontal position (see Fig. 7) arm 107 will have rotated through an angle such that its roller 108 engages the central recess 112 of the rocking lever 110 and locks said lever in this position, whereby its pin 114 locks the switch in its left-hand end position in which the heating element circuit 68 is closed.

On turning lever 73 further arm 107 will be rotated through a further angle in counter-clockwise direction, its roller 108 turning rocking lever 110 in clockwise direction until roller 108 engages the left-hand recess 113 of lever 110 (see Fig. 8). During this rotation rocking lever 110 by its pin 114 turns the switch into its right-hand end position, whereby the motor circuit is again closed.

At the commencement of the rotary movement of the lever 73 rinsing valve 58 can fall under its own weight, but washing valve 55 remains closed, pin 76 on the lever then sliding in the slot 77 of link piece 74. The washing valve 55 will be raised only when pin 76 abuts upper end of slot 77. This occurs during the second half of the rotary movement of lever 73, during which the circuit of the motor is still broken and, thus, washing pump is at a standstill so as to be unable to counteract the opening of the valve. The pin and slot connection 76, 77 renders possible a certain amount of play in the action of the

lever during which the motor can be switched-out without the valves being influenced.

In the embodiment shown the switch is operable not only by valve lever 73 but also through the intermediary of a thermostat. As mentioned above the bimetal body 91 is arranged at the bottom of rinsing chamber 50 in the vicinity of heating element 68. Fixed to the lower limb of element 91 (see Fig. 9) is a plate 115 presenting an angular notch 116 into which the suitably rounded end of a bar 117 engages, said bar being eccentrically conducted through a disk 118 on shaft 92 and secured in position by a screw 119. In this way the length of that portion of the bar 117 lying outside the disk 118 and hence the temperature at which the thermostat responds can be varied.

Shaft 92 or its extension carries inside the control box 67 an arm 120 cooperating with a stop 121 on frame 100. A spring 122 stronger than spring 105 tends to turn shaft 92 and hence also arm 120 in counter-clockwise direction in Fig. 9, stops 123, 124 fitted on the wall of the box limiting the rotation of arm 120.

In the system of operation of the switch as described above, it was assumed on setting handle 81 and lever 73 that the thermostat was switched-in as shown in full lines in Fig. 9, the temperature of the rinsing chamber, however, being less than that at which the thermostat responds. When this temperature is attained the lower limb of body 91 releases bar 117, whereby shaft 92 by spring 122 is turned in counter-clockwise direction in Fig. 9, arm 120 being thereby moved from the position shown in full lines in this figure into the position indicated by dash lines. In this new position of arm 120, the switch is on its setting checked in a central position in which it is without current and accordingly cannot be turned into its left end position, in which the heating element 68 is switched-on. By manual operation of knob 93, the thermostat may also be switched-on and off manually.

If the thermostat is switched-on but the temperature is still too low, then on the setting of the valves 55 and 58 from washing into rinsing position or conversely, the switch will accordingly switch in heating element 68 when lever 73 assumes its horizontal position, but when the thermostat has been switched-on either manually by means of knob 93 or automatically under the action of the temperature in the rinsing compartment, then the switch will on setting of the valves provisionally be maintained in its currentless position (dash lines in Fig. 9), being prevented by arm 120 from assuming the position shown in Fig. 7, since spring 122 is stronger than spring 105.

In the embodiment according to Fig. 11 the play of valve lever 73 is rendered possible in another way. At its lower edge lever is formed with a guide surface 125 cooperating with a roller 126 at the free end of an arm 127 which constitutes the operating member of a two-way switch 128 and may be operated by aid of a lever 129. In this case the motor is switched-on in both contact positions of the switch. The curvature of the guide surface 125 is such that in each rocking position of lever 73 the end portion of the surface forms an arc with the pivot of arm 127 as a centre. The initial and final portion of the rotation of arm 127, during which the motor will be switched-on or off, accordingly exercises no action at all on lever 73, the roller 126 merely sliding along these arcuate portions. The lever will be adjusted only at the commencement of the second half of the

rotary movement of arm 127, and the setting will be completed before the motor is switched-on again.

The invention is not limited to the embodiments shown which can be altered in several respects without exceeding the scope of the invention. Of course, it is obviously not tied down to built-in machines of the type shown, but is also applicable with equal advantage to self-contained types of machines. As already stated the machine can be provided with one valve only.

What I claim is:

1. In a dish washing machine, two pumps the one for washing liquid and the other for rinsing liquid, a flow control valve for each of said liquids, an electric motor for driving said pumps, a switch for controlling said motor, means for setting said valves so as to open and close them alternately, a manually operable control member, and means to connect said control member with the valve setting means and the switch so as to effect actuation of the valve setting means to open one of the valves, only when the switch is set to open the circuit of the motor.

2. In a dish washing machine according to claim 1, wherein the means to connect the control member with the valve setting means and the switch comprises means to effect actuation of the switch to close the circuit of the motor, only when said valve setting means is set to open one of the valves.

3. In a dish washing machine according to claim 1, wherein the means to connect the control member with the valve setting means and the

switch comprises means to effect adjustment of the valve setting means from a position in which one of the valves is open and the other closed, into a position in which the first-mentioned valve is closed and the last-mentioned valve open, only when the switch is set to open the circuit of the motor.

4. In a dish washing machine according to claim 1, wherein the switch is of the two-way type having two contact-making positions and an intermediate breaking path, the means to connect the control member with the valve setting means and the switch comprising means to open and close the valves alternately during the passage of the switch through said breaking path.

5. In a dish washing machine according to claim 1, wherein the switch is of the two-way type having two contact-making positions and an intermediate breaking path, the means to connect the control member with the valve setting means and the switch comprising means to close the circuit of the motor at both contact-making positions and to open and close the valves during the passage of said switch through said breaking path.

6. In a dish washing machine according to claim 1, wherein the switch is of the two-way rocking type and the valves of the lift valve type, the valve setting means including a rocking lever connected with said valves so as to open and close them alternately, a pivot for said rocking lever, and means to operate the switch by the actuation of said lever.

TORD ERIK DANIEL BILDE.
